UNITED STATES PATENT OFFICE

ANTONIO K. LAQUIDARA, OF NEW YORK, N. Y.

CORNICE MOLD

Application filed October 29, 1927. Serial No. 223,680.

This invention relates to improvements in cornice molds and particularly to mitre molds for plaster cornice work.

The primary object of the invention resides in a cornice mold in which the mitres or corners of a room may be smoothly finished during the molding of the cornice and by the same mold used during the molding operation and without lifting the mold from engagement with the work.

Another object is to provide a mitre mold having a molding edge, the vertical surfaces of which are pointed to provide right angular surfaces one of which lies flat against the wall as the mold is drawn thereacross, while the other is perpendicular to that wall and fits snugly against the adjacent wall as the mold is brought thereagainst after forming the cornice of one wall and by which the cornice on the next adjacent wall may be started without reversing the mold and which assures a smooth and clean joinder between the cornice of two adjacent walls and leaves the cornice smooth and finished.

A further object is to provide a mold of the above kind which embodies a guide mounted thereon for the assistance of a worker in setting the mold on the wall and for securing the necessary guide lines on the ceiling used for guidance when "running" the mold during the forming of a cornice.

A still further object is to provide a cornice mold which embodies all the features of the present mold with certain added features without materially increasing the cost of the same.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of my improved cornice mold.

Figure 2 is a side elevation of the same.

Figure 3 is a vertical transverse sectional view on the line 3—3 of Figure 2.

Figure 4 is a diagrammatic view showing

the different positions of the same during the use of the same.

Figure 5 is a fragmentary horizontal sectional view on the line 5—5 of Figure 2.

Figure 6 is an enlarged diagrammatic view showing the angular faces of the cutter edge with respect to two adjacent walls.

Referring more particularly to the drawing, the reference numeral 10 designates my improved mitre cornice mold in its entirety which includes a triangular shape base 11 having two right angularly disposed edges beyond which spaced guides 12 project for engagement with the walls in lieu of the entire edge whereby to decrease friction therebetween to assure a smooth and easy "running" of the mold. Mounted on the base and disposed at an angle of 45° with respect to the side edges thereof is a cutting plate 13, the front of which projects beyond the corner of the base to a plane even with the outer faces of the guides 12. The cutter plate is made of steel and is riveted or otherwise secured to an aluminum support 14 rising from the base and removably held by an angle strip 15 by bolts 16 while the angle bar is riveted to the base as clearly illustrated in Figure 3 of the drawings. The vertical cutting edges of the cutting plates are bevelled in opposite directions as at 17, the surfaces of which are disposed at 90° angle with respect to each other. The cutting edge may be of any design and the curves therein, if any, have their relatively vertical portions bevelled the same as the truly vertical edges and which bevels gradually merge into the flat horizontal edges. The purposes of these bevelled edges will be more fully explained herein-after.

For manually holding the mold, I provide a handle 18 which is constructed of a length of aluminum tubing flattened at its ends and bent to fit flat against the support 14 and the base 11 respectively. The handle is disposed rearwardly of the mold so that during the working operation, the cornice formed will not interfere with the hand grip of the user.

In the use of the mitre mold, the operator places the mold against the wall of a wall

cornice rod and proceeds to move the same horizontally across the wall from a position between two adjacent walls. For instance the operator starts at the position indicated at 5 A in Figure 4 and moves the mold from right to left across the wall E to a position marked B or until the angular bevelled surfaces on the cutter plate snugly fit and forms the corner in the cornice marked G. Instead of reversing the mold he continues partway across the adjacent wall marked F to the position marked C. The corner G having been formed, the mold is reversed to the position marked D and that wall completed in the 10 same manner and until the final corner of the room marked H has been formed. The angular faces on the cutter plate assure a smooth and finished corner and cornice which may be formed by a single operation of the 15 mold.

Mounted on the top of the supporting plate 14 is a mold guide 20 having right angularly bevelled faces 21 and which may be engaged by the ceiling cornice rod, but this is not absolutely necessary. However, these edges 25 may be used for the purpose of markings to receive the guide line.

From the foregoing description, it will be seen that I have constructed a mitre mold 30 which is capable of performing the functions of the molds now in use, in addition to the automatic completion of the corners of a cornice during the "running" of the mold from one wall to the next adjacent wall. This 35 method will greatly reduce the time for such work and produce a smooth and finished job.

While I have described what I deem to be the most desirable embodiment of my invention, it is obvious that many of the details 40 may be varied without in any way departing from the spirit of my invention, and I therefore do not limit myself to the exact details of construction herein set forth nor to anything less than the whole of my invention limited 45 only by the appended claims.

What is claimed as new is:—

1. In a cornice mold, a base, a molding plate rising from and supported by said base and having vertical and horizontal molding 50 edges, the vertical molding edges being bevelled in opposite directions at right angles to each other while said horizontal edges are flat.

2. A cornice mold comprising a substantially triangular shape base having two right angularly disposed edges, and a molding plate mounted on said base and extending from the corner of the joinder of said right angularly disposed edges at an angle of approximately 45° with respect to said edges, said molding plate having vertical, horizontal and curved molding edges, the vertical molding edges of said cutting plate being bevelled in opposite directions and curved 55 while the horizontal edges are flat.

3. In a cornice mold having a molding blade provided with vertical, horizontal and curved molding edges, all of said vertical and curved edges being bevelled at 90° on a horizontal plane while said horizontal edges are flat. 70

4. In a cornice mold having a molding blade provided with a cornice forming edge bevelled at right angles, a series of like edges disposed in parallel planes so that when the molding blade is held at an angle of 45° with respect to the side wall on which a cornice is to be formed, one of the bevelled right angular edges thereof is disposed parallel to the side wall in a horizontal direction, while the other bevelled right angular edge will be disposed perpendicular to the wall in a horizontal direction. 75

In testimony whereof I have affixed my signature. 80
